BLANKET

Hugo William Palm, Pequannock, N. J.

Application April 24, 1934, Serial No. 722,171

2 Claims. (Cl. 5—334)

This invention has reference to blankets, and an object of the invention is to provide a blanket that will render sleeping more comfortable, that will relieve the bed maker of much labor and annoyance, and that will prolong the usefulness and wear of the blanket.

In accordance with the present invention the blanket is provided at the foot end thereof in a manner to be so engaged with the mattress as to prevent displacement of the blanket at the foot of the bed by the sleeper as is now often done when the occupant of the bed attempts to pull the bed covering up over the shoulders.

More particularly the invention is concerned with improvements in what are known in the art as "double blankets" and the invention together with its objects and advantages will be best understood from a study of the following description taken in connection with the accompanying drawings wherein:

Figure 1 is a plan view of a bed having my improved blanket thereon.

Figure 2 is a fragmentary plan view showing the manner of associating the foot end of the mattress with the blanket.

Figure 3 is a fragmentary view partly in section and partly in elevation illustrating the pocket formed in accordance with this invention, one end of the mattress being shown arranged in the pocket, and

Figure 4 is a fragmentary sectional view taken substantially at right angles to Figure 3.

In the drawings 5 indicates generally a bed provided with the usual mattress 6, and as illustrated, also provided with a double blanket indicated generally by the reference numeral 7, and embodying the features of the present invention, together with the usual pillows 8.

The blanket 7 is substantially of the standard double blanket type and includes the folds 9 and 10. In accordance with the present invention one of the folds, for example the fold 10 inwardly from the fold line, that is to say the folded end

of the blanket is provided with a slot 11 that as clearly shown in Figure 2 extends transversely of the blanket and terminates inwardly from the longitudinal edges of the blanket. The edge of the blanket defining the slot 11 is reinforced by a tape 12 of any suitable material secured thereto in any suitable manner, preferably by stitching. It will thus be seen that at the folded end of the double blanket there is formed a pocket 13.

In accordance with the present invention the foot end of the mattress 6 is inserted into the pocket 13 through the slit or slot 11 as thought clear from a study of Figures 2 to 4 with the top face of the mattress being covered by the folds 9 and 10 of the blanket.

It will be apparent that with the end of the mattress 6 within the pocket 13 it is practically impossible to pull the foot end or folded end of the blanket from between the foot end of the mattress 6 and the foot rail of the bed no matter how hard a pull may be exerted on the blanket.

In addition to the fact that in accordance with this invention sufficient means is provided to prevent kicking of the foot end of the blanket from its proper place, also the invention makes for easier bed-making, neatness of appearance at the foot of the bed, and retention of the sheet and other bed covers in place at the foot end of the bed.

Having thus described my invention, what I claim as new is:

1. As a new article of manufacture, a double blanket having one fold thereof adjacent the folded end of the blanket provided with a transverse slot for accommodation of an end portion of a mattress.

2. A blanket folded upon itself to provide at the folded end thereof a pocket, one fold of said blanket being provided with a transverse slit forming a mouth at one side only of the blanket for said pocket.

HUGO WILLIAM PALM.
